UNITED STATES PATENT OFFICE.

JAMES WILLIAM KENNEDY, OF BURKE, NEW YORK.

NON-REFILLABLE BOTTLE.

No. 866,477.

Specification of Letters Patent.

Patented Sept. 17, 1907.

Application filed April 22, 1907. Serial No. 369,501.

To all whom it may concern:

Be it known that JAMES WILLIAM KENNEDY, a citizen of the United States, residing at Burke, in the county of Franklin and State of New York, has invented certain new and useful Improvements in Non-Refillable Bottles, of which the following is a specification.

This invention relates to bottles and more particularly to that class known as non-refillable bottles.

10 The object of this invention is to produce a bottle simple in construction, inexpensive to manufacture, and one that cannot be refilled without detection.

My invention broadly consists in the construction, combination and arrangement of parts to be hereafter 15 more specifically described and fully pointed out in the claims.

In the drawings: Figure 1 is a side elevation. Fig. 2 is a vertical section on the line 2--2 of Fig. 1.

Referring specifically to the drawings the body is 20 indicated at 5, having a neck portion 6, threaded as at 7. To the threaded portion 7 of the neck 6, is secured a nozzle 8, which comprises the upper and lower sections 9 and 10 respectively. The lower section 10 is internally threaded as at 11, and adapted to be screwed 25 to the portion 7 of the neck 6. A recess 12 is formed in the section 10 and communicating therewith and with the body 5 of the bottle is a passage 13.

Extending through the passage 13 and into the bottle is a tube 14, carrying on its lower end a spring 15 30 adapted to engage the lower portion 10' of the section 10. The upper end of the tube 14 carrying a valve seat 16 to receive a ball valve 17. By thus constructing the tube 14, it will be seen that it is securely locked to the section 10 of the nozzle. The upper portion of 35 the nozzle 10 is internally threaded as at 18, adapted to receive a threaded portion 19 of the section 9 of the nozzle. An angular passage 20 is formed in the section 9 which enters at its lower end into the recess 11; and

at its upper end opens into an annular recess 21, into which is placed a cork or other closure 22.

The section 9 is recessed as at 23 and is adapted to aline with the recess 12 in the portion 10, thus forming a chamber 24 for the movement of the valves 17. A label 25 is pasted to the nozzle 8 and over the joint 45 formed by the sections 9 and 10, which will of course be broken in an attempt to unlock said sections.

After filling a bottle ready for the market the threads 7 on the neck 6 of the bottle are first coated with cement, 50 the section 10 is then screwed thereto, and its interior threads 19 coated likewise with cement, and the section 9 screwed thereto. A label is then pasted around the bottle and over the joints formed by the sections 55 9 and 10 thereof, and the bottle closed by a cork.

When it is desired to remove the contents of the bottle the bottle is inverted, whereupon the valve 17 will roll into the chamber 24 and the liquid allowed to flow 60 through the passage 20.

The angular passage 20 prevents an attempt to tamper with the valve 17. A piece of wire or the like which might be inserted in the passage 20 would be directed in a course away from said valve.

What is claimed is:

In a bottle the combination of the body portion provided with a threaded neck, a section nozzle threaded thereto, said nozzle comprising upper and lower sections, the lower section having a recess formed therein and a passage communicating with the recess and with the bottle, an upper section screwed to the lower section and having a recess adapted to aline with said first mentioned recess to form a chamber, said upper section having an angular passage therein in communication with said chamber, and 70 75 a valve in the chamber arranged to close the passage of the lower section.

In testimony whereof he affixes his signature, in presence of two witnesses:

JAMES WILLIAM KENNEDY.
